(57) **CLAIM**

The ornamental design for a luggage case, as shown and described.

DESCRIPTION

FIG. 1 shows a front perspective view of a luggage case showing the new design;

FIG. 2 shows a front elevation view of the luggage case of FIG. 1;

FIG. 3 shows a rear elevation view of the luggage case of FIG. 1;

FIG. 4 shows a right elevation view of the luggage case of FIG. 1;

FIG. 5 shows a left elevation view of the luggage case of FIG. 1;

FIG. 6 shows a top view of the luggage case of FIG. 1; and, FIG. 7 shows a bottom view of the luggage case of FIG. 1. The broken lines in FIGS. 1-7 illustrate portions of the luggage case that form no part of the claimed design.
